UNITED STATES PATENT OFFICE.

JOHN ACE ROBERTS, OF CARDIFF, ENGLAND.

CRANE-BUCKET.

987,492.

Specification of Letters Patent. Patented Mar. 21, 1911.

Application filed May 14, 1910. Serial No. 561,352.

To all whom it may concern:

Be it known that I, JOHN ACE ROBERTS, a subject of the King of Great Britain, residing at 21 Park Place, Cardiff, Glamorgan-shire, Wales, England, have invented new and useful Improvements in Crane-Buckets, of which the following is a specification.

My invention relates to crane buckets for use in coaling, excavating, building and other operations, and more particularly to that class of such buckets wherein the sides are adapted to be lifted relatively to the bottom for the purpose of discharging the contents, the object of my invention being to construct a bucket of this kind which is suspended by a single rope, and which can nevertheless be discharged by the driver of the crane working the bucket.

According to my invention I attach to the bottom a stem or standard the upper end of which is united by a rod to one end of a link or bar having recesses in which a ring or the like on the crane chain or rope engages, and the body is provided with trunnions or the like to which the bucket bail is connected, the free end of the said bail being pivotally attached to the other end of the link.

To enable my invention to be fully understood I will describe the same by reference to the accompanying drawings in which:—

Figure 1 is a sectional elevation, and Fig. 2 is a plan of a crane bucket arranged in accordance with my invention. Fig. 3 is a view similar to Fig. 1 of a modification but showing the bucket in the position for the discharge of the contents.

a indicates the body of the bucket, which, as shown is of circular section, and *b* indicates the conical bottom, *c*, *c* being guide rods fixed to the latter which work in the guide sockets *d*, *d* on the body.

e is the bail of the bucket which is connected to trunnions *f*, *f* thereon, and *g* is the stem or standard which is fixed to the bottom *b*.

h is the link or supporting bar on which a ring or eye *i* on the crane chain or rope slides, the said link having in it the two recesses *j*, *j'* in which the ring can engage. This link *h* is at one end pivotally attached to the bail *e* and at the other end is pivotally connected by a rod *k* to the upper end of the stem or standard *g*. The connecting rod *k*, bail *e* and link *h* are of such relative lengths

that when the body *a* rests upon the bottom *b* as shown in Fig. 1, the ring *i* of the crane will lie in the recess *j* over the center of the bucket. Upon the extended end *h*² of the bar *h* adjacent to the recess *j* is arranged a weight *l* (or if desired this weight may be fixed upon the rod *k* as shown in Fig. 3) the normal tendency of which will be to swing the link *h*, rod *k* and bail *e* in the direction of the arrow 1, Fig. 1, so that when the crane ring is dropped out of the recess *j* the said link *h* with the connected parts will be thrown over to the position indicated by the dotted lines in Fig. 1, whereby the recess *j'* will be brought into proximity to the ring *i*. If, now, the crane-chain is drawn up the effect will be to lift the body *a* independently of the bottom *b* so that the parts will assume the position shown in Fig. 3, any material within the bucket being discharged from the same by sliding off the conical surface *b* of the bottom.

When the bucket is loaded the parts are in the position shown in Fig. 1, that is to say, with the ring *i* in the recess *j*; when the contents are to be discharged the bucket is dropped on to the ground or heap so that the weight *l* operates as before described to throw over the bail *e*, whereby, on the chain being again drawn up, the contents will be discharged. To close the bucket it is again dropped on to the ground or heap, whereupon the body *a*, owing to its weight, drops on to the bottom, while the ring and chain will fall or slide down the link toward the recess *j* as indicated by the dotted lines in Fig. 1. While in this position the bucket is ready for loading.

A cord *m* or the like may be attached to the lifting chain for retaining the ring *i* in the recess *j* so that when the crane chain is again drawn up, the link *h* and connected parts will be thrown over to the position shown in full lines in Fig. 1 for the bucket to be hoisted away.

n is a stop placed upon the sides of the bucket for preventing the bail from falling over too far in the direction of the arrow 2.

The bucket hereinbefore described is very advantageously used for loading or discharging lump coal as it enables the latter to be handled with a minimum of breakage.

Claims.

1. A crane bucket comprising a main body and a bottom connected therewith to slide toward and from the main body, a standard

connected centrally to said bottom, a bail pivoted to said main body, and a link or supporting bar connected at one end to said bail and at its opposite end connected with 5 said standard, said supporting bar being provided with two recesses, one near the end connected to said bail and the other near its opposite end, whereby when the recess near the bail end of the supporting bar is centrally over the bucket the bottom is permitted to descend to discharge the contents of 10 the bucket and when its other recess is in said position the bucket will be closed.

2. A crane bucket having a main body and 15 a bottom connected therewith to slide toward and from the main body, a standard connected centrally to the said bottom, a bail pivoted to said main body, a supporting bar connected at one end to said bail and 20 near its opposite end connected by a link to the said standard, the said supporting bar having a recess near the end at which it is connected to said bail and another recess near its connection to said link,

the said construction including a weight 25 secured to one of said parts to cause the said supporting bar when released from burden to move in a direction to bring the recess near the bail centrally above the bucket.

3. A crane bucket having a main body 30 and a bottom connected therewith to slide toward and from said body, a standard connected centrally to said bottom, a bail pivoted to said main body, a supporting bar connected at one end to said bail and 35 having its opposite end connected with said standard, said supporting bar having near each end a recess for engaging the means for supporting the bucket, and a weight secured to the end connected with said standard tending when the supporting means is slackened, to move the parts to bring the bail approximately centrally over the said bucket.

JOHN ACE ROBERTS.
